Primary Examiner — T Chase Nelson

Assistant Examiner — Sydney Margaret Parsley

(57) **CLAIM**

The ornamental design for a sitting board for ladder, as shown and described.

DESCRIPTION

1. Sitting board for ladder

1.1 : Perspective

1.2 : Perspective

1.3 : Front

1.4 : Back

1.5 : Left

1.6 : Right

1.7 : Top

1.8 : Bottom

1.9 : Enlarged

The parts shown by means of broken lines in the reproductions are not part of the claimed design; fig. 1.9, is the enlarged view of the portion taken at line 1.9 in fig. 1.1; the dash dot dash broken lines in fig. 1.1 represent boundaries for the enlarged view in fig. 1.9 and form no part of the claimed design.

1 Claim, 9 Drawing Sheets
